UNITED STATES PATENT OFFICE.

EVERARD RICHARD CALTHROP, OF LONDON, ENGLAND, ASSIGNOR TO E. R.
CALTHROP'S AERIAL PATENTS LIMITED, OF LONDON, ENGLAND.

PARACHUTE.

1,345,582.

Specification of Letters Patent.

Patented July 6, 1920.

Application filed March 25, 1919. Serial No. 285,133.

To all whom it may concern:

Be it known that I, EVERARD RICHARD CALTHROP, a subject of the King of Great Britain, residing at London, in the county of Middlesex, England, have invented new and useful Improvements Relating to Parachutes, of which the following is a specification.

This invention has reference to parachutes adapted to be carried by aerial craft to afford means whereby the occupant or occupants may descend safely to the ground in case of emergency.

The primary object of the present invention is to provide improved means for carrying a parachute upon an aerial craft in such a manner that the container therefor shall offer a minimum resistance to the air-current in flight and during the launching operation assume such a position as to offer a minimum resistance to the extraction of the parachute and its associated parts irrespective of the speed and position of the aeroplane to the air current created thereby.

Further objects are to provide improved means for mounting the parachute container constituting the launching device upon an aerial craft in any desired position without making any structural alterations to the fuselage and to provide means for holding said device rigidly in position and for automatically releasing it from its normal position when the load is applied.

In the accompanying drawings:—

Figure 1 is a diagrammatic view of my improved parachute launching device illustrating its application to the upper portion of the fuselage of an aeroplane.

Fig. 2 is an end view of the device mounted at the side of the fuselage.

Fig. 3 represents a section through the container for the parachute and its associated parts shown in Fig. 1.

Fig. 4 is a similar section of the container illustrated in Fig. 2.

Fig. 5 represents a section drawn to a larger scale through a portion of the container illustrated in Fig. 4 and

Fig. 6 is a sectional plan view of Fig. 5 taken along the line $a-a$ of that figure.

Figs. 7 and 8 are detail views hereinafter more particularly referred to.

Fig. 9 is a detail view of a part of the device employed in connection with the ar-

rangement illustrated in Fig. 1 and to be hereinafter more fully described.

In that embodiment of my invention illustrated in Figs. 1 and 3 the container—indicated as a whole by the letter A—is streamlined or approximately torpedo-shaped and is formed of two parts 1 and 2 capable of being assembled together by a joint 3 adapted when the load is applied to separate to permit of the launching of the parachute therefrom as hereinafter explained.

The portion 1 of the container A is adapted to fit into the portion 2 to form the pull-out joint 3 which is of such a character that it shall be weather proof and air tight to which end I prefer to arrange a felt packing ring 4 on the portion 1 of the container (Fig. 7) and against which the interior of the mouth of the part 2 wedges tightly when the two portions are assembled. A fabric cover 5 attached to the part 1 overlaps the junction of the two parts and effectually renders the joint weather-proof.

The portion 1 of the container is adapted to receive the plaited and folded parachute body 6 which is secured by its apex to said portion by a detachable or rupturable connection 7 while within the portion 2 of said container the tapes constituting the rigging of the parachute are housed. The method I adopt of assembling said parachute and its rigging will be best understood from an inspection of Fig. 7 which illustrates diagrammatically the relative connections between the parts the two portions of the aforesaid container A being shown as separated slightly as would happen when the load is first applied to the portion 2 through the center bolt 8 to which the aviator is attached by the usual load rope shock absorber and harness. One of the tapes constituting the rigging and arranged in a pack (as described in my prior specification No. 21312 of 1914) is indicated by the numeral 9 one end of said tape being positively connected to the portion 2 of the container A as at 10 while the opposite end of said tape is attached to the periphery of the parachute body as at 11 by means of a toggle and gromet or other suitable connection.

The other portion 1 of the container which it will be understood normally fits into the mouth of the portion 2 carries a ring 12 to which a cord 13 is attached the

other end of said cord being connected by a rupturable connection 14 to the aforesaid toggle. For the sake of clearness only one tape 9 and its connections to the parachute body and portion 1 of the container is shown in the figure under consideration but it may here be mentioned that in the standard parachute there are twenty-four such rigging tapes and obviously there will be twenty-four packs of tape within the portion 2 of the container and twenty-four connections 13 and 14 within the portion 1 of the container.

The parts being assembled as described and the two portions 1 and 2 of the container fitted together it is apparent that means must be provided for retaining the said parts of the container in close and operative relation and this is effected by the rupturable connection preferably of light gage wire 15 (Figs. 3 and 4) which is positively attached by one end to the apex of the portion 1 of the container while the other end is secured to a loop 16 of wire to which the requisite tension may be applied through the ratchet arrangement 17 illustrated in Figs. 5 and 6 the operation of which is self evident without further description. By this means the two portions 30 of the container with the assembled parachute and rigging will be held securely together.

I will now proceed to a consideration of the means for mounting the container A upon the upper portion of the fuselage of an aeroplane for which purpose Figs. 1 and 9 will be particularly referred to. Clamped to the longerons of the fuselage is a bracket 18 to which an arcuate member 19 is secured appropriate connections 20 (which may be of a character adapted to be ruptured when the weight of the load is applied to the center bolt or adapted to be severed by an appropriate cutting mechanism) being provided to support that end of the container A which carries said center bolt 8. The opposite or forward end of the container is supported through a universal joint 21 carried by a bar 22 pivotally mounted as at 23 within the fuselage in such a manner as to be capable of transverse movement through a slot 24 in the fairing provided for that purpose. It will be seen that by these means the container A is held above the fuselage behind the aviator's seat and in order that a descent may be made from either side of the machine the load rope 25 which is attached by its loop 26 to the aviator's harness is bifurcated as at 27 and the two ends laid one on each side of the container A and positively connected to the center bolt 8. The object of thus bifurcating the load rope is to insure that its main portion shall be so positioned relatively to the container A that it shall always be in

readiness to fall to that side of the fuselage from which the aviator jumps.

Referring now particularly to Fig. 9 it will be seen that the forward end of the container is attached by the universal joint 21 to the bar 22 and the purpose of this arrangement is to permit of the container A being swung bodily to either side of the machine as the aviator may select when a descent is to be made and to secure automatic release of the container to allow of this the load rope 25 is normally supported in a forked member 28 pivotally attached at 29 to the bar 22. The member 28 is provided with a link 30 connected to a plunger 31 engaging a socket 32 positively secured to the fuselage.

It should here be noted that the method of mounting the container as hereinbefore described insures its rigid support when in the normal position this being accomplished as to one end by a joint which is rigid in compression but universal in tension and as to its other end by a rupturable connection adapted to maintain the container normally in compression.

The operation of this form of my invention will now be described. On the aviator throwing himself from the cock-pit—and it is to be observed that owing to the provision of means just described it is immaterial which side of the fuselage he selects for this purpose the forked member 28 will be turned about its pivotal point to that side of the aeroplane from which he has dived and the plunger 31 will be withdrawn from the socket 32 whereupon owing to the provision of a rupturable or resilient connection 33 between the load rope 25 and the head of the bar 22 the said bar will be given an impulse to begin its travel to the side of the fuselage carrying the front end of the container with it. The weight will now be exerted through the bifurcated load rope 25 to the center bolt 8 the connections 20 will be broken or severed and the continued application of the load will cause the bar 22 to move laterally until checked by the upper longeron so that the container A projects clear of the side of the fuselage and assumes an angular position of least resistance. The full weight being now exerted upon the center bolt 8 and wire 15 this latter will snap and the portion 2 of the container will separate from the portion 1 and in so doing will extend the tapes 9 constituting the rigging to their full length whereupon the periphery of the parachute body will be drawn out of the container in a circle owing to the extension of the cords 13 (Fig. 7) thus insuring entry of sufficient air to the interior of the parachute body to insure its eventual complete expansion. When the cords 13 are extended the weight of the load will be exerted on the rupturable connections 14 which

will snap thus releasing the periphery of the parachute and rendering it free to expand to its full extent. It will be apparent that if all the cords 13 were of the same length 5 the strain would be exerted on all the breaking pieces 14 simultaneously and the cumulative effect of this might rupture some part of the apparatus. To avoid this contingency said cords 13 are of varying lengths so that 10 the breaking pieces 14 are ruptured dis-synchronously.

Fig. 2 illustrates one method of carrying the launching device at the side instead of at the top of the fuselage and in this arrangement the container is supported at one 15 end by a universal joint from a bracket projecting from the side of the fuselage and the other end carrying the center bolt 8 is supported by the bracket 33 by means of a rupturable connection 34 which may be adapted 20 to be broken by the weight of the load or may be severed by a cutting mechanism 35 operated by a connection 36 with the load rope 25 before the weight of the load is exerted on the center bolt 8. The container 25 will then swing down vertically about the aforesaid universal joint and the parachute launched as above described. In this arrangement the usual shock absorber 25^a may conveniently be carried within the fuselage 30 and covered by a stripping piece 25^b of fabric so that no additional head resistance shall be created.

In Fig. 4 I have illustrated a slightly 35 modified form of container adapted for use with parachutes of the kind described in my specification of prior date No. 118859 wherein the mouth of the parachute is positively expanded by spring members. In 40 this modification the portion 1 of the container is provided at its interior with a cylindrical portion 37 to provide an appropriate surface for preserving the position of the spring members described in said prior 45 specification while the parachute is housed in the container.

Means may be provided for returning the 50 empty container to approximately its original position after a descent has been made and this may be effected by a rubber spring 55 38 attached respectively to the container and to the side of the fuselage and passing over a pulley or guide roller 39. To form a seating for the container when in the normal position a saddle shaped bracket 40 is provided being secured by a clamp to one of the longerons.

In the specification forming part of my 60 application for a patent No. 17062 dated October 18th 1918 I have described means for positively opening the gussets of a 65 parachute as it is launched said means comprising rupturable connections between certain portions of the periphery of the parachute body and the container and in Fig. 7 of

the accompanying drawings I have illustrated at 41 one of such connections the operation of which will be understood from the aforesaid prior specification.

In the foregoing description of my invention I have shown and illustrated the container as being carried either on the top or at the side of the fuselage but it is obvious that with slight modifications unaffected the scope of the invention the container may be mounted in any other desired position such as beneath the fuselage or the wings of an aeroplane or it may be attached to the under carriage.

The detail view Fig. 8 illustrates the method 80 of clamping the brackets to the longerons said brackets and clamps being all constructed of metal plates and arranged edgewise so as to offer a minimum of head resistance during flight.

What I claim and desire to secure by Letters Patent of the United States is:

1. A parachute launching device comprising a two-part streamline container within which the parachute and its associated parts 90 are nested, a universal joint for supporting one end of the container on the fuselage of an air craft and a rupturable connection for supporting the other end of the container and adapted to maintain the container normally in position.

2. A parachute launching device comprising a two part streamline container within which the parachute and its associated parts are nested, a universal joint for supporting 100 one end of the container on the fuselage of an air craft, a rupturable connection for supporting the other end of the container, a center bolt in the container, a load rope for connecting an aviator to the center bolt, and 105 a bifurcated end on said rope.

3. A parachute launching device comprising a two part streamline container within which the parachute and its associated parts are nested, a universal joint for supporting 110 one end of the container on the fuselage of an air craft, a rupturable connection supporting the other end of the container a center bolt in the container, a load rope for connecting an aviator to the center bolt and 115 a bar pivotally mounted within the fuselage for supporting the universal joint.

4. A parachute launching device comprising a two part streamline container within which the parachute and its associated parts 120 are nested, a universal joint for supporting one end of the container on the fuselage of an air craft a rupturable connection for supporting the other end of the container, a center bolt in the container, a load rope for 125 connecting an aviator to the center bolt, a bar pivotally mounted within the fuselage for supporting the universal joint and a connection between said bar and the load rope.

5. A parachute launching device comprising a two-part streamline container within which the parachute and its associated parts are housed, a universal joint for supporting one end of the container on the fuselage of an air craft, a rupturable connection for supporting the other end of the container, a center bolt in the container, a load rope for connecting an aviator to the center bolt and a forked member for supporting the load rope.

6. A parachute launching device comprising a two part streamline container within which the parachute and its associated parts are housed, a universal joint for supporting one end of the container on the fuselage of an air craft a rupturable connection for supporting the other end of the container, a center bolt in the container a load rope for connecting an aviator to the center bolt a bar pivotally mounted within the fuselage for supporting the universal joint and a forked member for supporting the load rope

said member being pivotally attached to the said bar.

7. A parachute launching device comprising a two-part streamline container within which the parachute and its associated parts are nested, a universal joint for supporting one end of the container on the fuselage of an air craft, a rupturable connection for supplying the other end of the container, and a rupturable connection between the two parts of the container.

8. A parachute launching device comprising a two part streamline container within which the parachute and its associated parts are nested, a universal joint for supporting one end of the container on the fuselage of an air craft, a rupturable connection for supporting the other end of the container and means for returning the empty container to its normal position relatively to the fuselage after the parachute has been launched.

EVERARD RICHARD CALTHROP.
